UNITED STATES PATENT OFFICE.

MATTI NIEMI, OF SEATTLE, WASHINGTON.

MUSIC-LEAF TURNER.

Application filed July 13, 1925. Serial No. 43,222.

This invention relates to music-leaf turners and, more especially, to improvements in the apparatus illustrated and described in U. S. Patent No. 1,484,308, issued to me

5 February 19, 1924.

Its object being to improve the construction of the apparatus above referred to to render the same more efficient and convenient to use.

10 With these ends in view the invention consists in the novel construction, adaptation and combination of parts hereinafter described and claimed.

In the accompanying drawings,—

15 Figure 1 is a front elevation of a music stand embodying my improvement; Figs. 2 and 3 are horizontal sectional views taken on lines 2—2 and 3—3 of Fig. 1; and Fig. 4 is a perspective view of a portion of the 20 pedal support.

Referring to the drawings, the numeral 5 represents, generally, the post member of a music stand comprising telescopically arranged parts 6 and 7. Said post is supported upon two front legs 8 and a rear leg 9 which are pivotally connected to a collar element 10 secured to the lower end of the post part 6 and connected by braces 11 with a sleeve 12 which is secured in adjusted 30 positions to the post as by means of a latch 13. Detachably connected to the post part 7 is a vertical extension 15 to the lower portion of which are hingedly connected by means of pivot 16 bracket members 17.

35 Each of said bracket members is in the nature of an angle-bar having a horizontal flange element 17¹ and a vertical flange element 17².

40 18 represent foldable link elements connected to the post extension 15 and said bracket members, and cooperating with wing bars 19, which are pivotally connected to each other and said links, to afford a backing for music sheets which are held in place as 45 by means of spring wire arms 20 attached to pivot pins 21, as shown.

The lower ends of such sheets are engaged in clips 22 secured to the bracket flanges 17². The parts above described constitute a 50 known construction of music stand.

In the present invention, like that illustrated in the aforesaid patent, there is provided upon each of the brackets 17 a lever

which by means of a pin 23 is fulcrumed to the respective horizontal flanges 17¹ to 55 provide relatively short and long lever arms 24 and 24¹.

The longer arms 24¹ carry devices which will be presently described for holding a 60 sheet of music.

To accommodate the horizontal swinging movements of the lever arms 24, the bracket flanges 17² are slotted as at 25¹.

The music leaves which are to be turned are carried by the longer arms 24¹ and to 65 connect the leaves thereto, upon each of these arms there is provided a vertical rod 25 hingedly connected to a carrier 26 which is adjustably slidable upon the arm, said rod being provided adjacent its upper end a clip 70 27 within which is engaged the outer edge of the upper portion of the music leaf as L in Fig. 1.

The lower edge of a music leaf is held 75 against a fence element 28, carried by the lever arm 24¹, by means of a clamping piece 29 pivotally connected to the respective rod 25 and engageable between such leaf and a post element 30 extending upwardly from the lever arm. Said clamping piece is 80 formed of wire and is bent back upon itself to afford an end 29¹ Fig. 2 which cooperates with the main portion of the clamping piece to constitute, in effect, a sear spring for urging the leaf against said fence. 85

Similarly to the carrier 26 for the rod 25, the fence 28 is adjustably slidable on the lever arm 24¹ toward and from the axes of the pivotal connections 23 of the latter for the purpose of regulating the positions of 90 the leaf holding devices suitable to different widths of leaves. The clamping piece 29, which cooperates with the fence 28, is shifted with the rod 25 to which it is connected by moving the carrier. 95

The shorter arm 24 of each of said levers terminates in laterally extending perforated ears 31 and 32 to which are attached the ends of flexible connections 31¹ and 32¹, preferably of wire, extending through leads 33 and 100 34, provided upon the respective bracket members 17.

The other ends of the wire connections 31¹ and 32¹ are attached to ends of flexible connections 31² and 32², preferably cords, which 105 extend downwardly and thence about rollers

35 provided in the outer ends of pedal devices 36 to a winding drum 37, one on each pedal device.

Said pedal devices are in the nature of 5 levers which are each fulcrumed at its mid-length by means of a pin 38 to spaced apart standards 39 extending upwardly from a floor plate 40—common to both pedals—disposed transversely with respect to the music 10 stand.

To each of its ends said floor plate is pivotally connected at 41 to an end of a link 42 whose other end is notched as at 43 to cooperate with a hook 44 pivoted to the link 42 15 for connecting the floor plate to the adjacent stand leg 8. 45 represents a notched offset arm provided upon a link 42 to engage a leg 8 above its engagement with a link to render more rigid the connection of the latter with the stand.

The drums 37 are rotatably mounted upon the respective pins 38, see Figs. 1 and 3, each of said drums being rotatable to wind the cords—31² or 32²—thereon by means of a 25 clock spring 46 acting through the medium of a toothed gear 47 mounted upon the spring shaft 48 engaging a pinion 49 which is rotatable with the respective drum. The purpose of the cord take-up afforded by the 30 spring actuated drums is to render the cords taut for various vertical adjustments of the stand. After the cords are thus regulated the drums are secured against rotary motion by means of wire dogs 50 engageable with 35 peripheral teeth provided on the drum ends 51.

As shown said dogs are provided with finger elements 52 for rotating the dogs into engaged and disengaged relations with the 40 drum. 53 represent eye attachments for directing the cords to the respective drums.

The cords 31² and 32² are arranged to be disconnected from the respective wires 31¹ and 32¹ by means of hooks 54 provided upon the cords engageable with eyes 55 provided upon the respective wires.

In operation, a sheet of music attached to either of the lever arms 24¹ is turned about the axis of the respective fulcrum pin 23 50 through the medium of the flexible connections and the associated pedal lever 36. By depressing the more elevated arm of the pedal lever a pull is imparted through flexible connection thereof to cause the sheet-supporting lever to be swung in such a man-

ner as to turn the sheet and swing the same from one side of the stand axis to the other side.

Among the advantages of the present improvements are:

Improved means for holding the leaves to the stationary and relatively movable or swinging parts, respectively, of the upper portion of the stand.

Another improvement resides in the manner or means for foldably connecting the various parts of such upper portion of the stand to permit the same to be readily collapsible into a small space and to be quickly expanded into operable condition.

The means afforded by the spring actuated drum devices on the pedals for taking up the slack in the flexible connections are of importance as are also the pawl devices for securing the drums to retain the flexible connections in operative conditions.

The take up means accommodate the cords to different vertical adjustments of the stand—and also serve to wind up the cords 31² and 32² when they are disconnected from the wire connections 31¹ and 32¹.

What I claim, is,—

In a music leaf turner of the character described, the combination with a stand having a central post element, bracket members pivotally connected thereto, and link elements foldably connected together and pivotally connected to the post and the respective bracket members for supporting the outer ends of the latter, of wing bars connected to 85 said link elements, resilient means cooperating with the respective links and wing bars for detachably connecting sheets of music thereto, arms pivotally connected adjacent to one end of each to the respective bracket members, each of said arms having slidably mounted thereon a fence member and a carrier, a rod pivotally connected to said carrier and provided near its upper end with a leaf engaging clip, and a clamping piece 95 pivotally connected to said rod and adapted to cooperate with the fence member for connecting the lower portion of a leaf to said arm, the upper portion of said leaf being connected to the respective clip whereby the 105 said leaf is turnable about the pivotal axis of said arm.

Signed at Seattle, Washington, this 8th day of June, 1925.

MATTI NIEMI,
